UNITED STATES PATENT OFFICE.

JAMES MCKECHNIE, OF BARROW-IN-FURNESS, COUNTY OF LANCASTER, ENGLAND, AS
SIGNOR TO VICKERS LIMITED, OF WESTMINSTER, ENGLAND.

MEANS FOR SUPPLYING LIQUID FUEL TO INTERNAL-COMBUSTION ENGINES.

Application filed February 28, 1921. Serial No. 448,498.

To all whom it may concern:

Be it known that I, JAMES MCKECHNIE, a subject of the King of Great Britain, residing at Naval Construction Works, Barrow-in-Furness, in the county of Lancaster, England, have invented new and useful Improvements in or Relating to Means for Supplying Liquid Fuel to Internal-Combustion Engines, of which the following is a specification.

This invention relates to means for supplying liquid fuel to internal combustion engines of the type in which liquid fuel is injected at high pressure and without the aid of injecting air into the compression space of the engine cylinder. For such injection resilient accumulator pressure is desirable and this has usually been obtained hitherto by pumping the fuel against resilient pressure in a special chamber or accumulator associated with the fuel supply pipe.

According to this invention the fuel is delivered by a pump into a tube or hollow rail which conveys the fuel to the injection valve or valves of the cylinder or cylinders of the engine, the volume and proportions of the said tube or rail being such that the tube or rail constitutes a resilient accumulator which under the pressure produced by the pump accommodates the required fuel charge and maintains the pressure at the injection valve or valves at the high level required during the valve opening. The tube is of considerable length, necessarily so in a multi-cylinder engine (where it extends across a number of cylinders and is then sometimes referred to as the rail), and yields throughout its length to provide the required charge volume. It may be cylindrical in cross section, or oval or flattened to provide for such yielding as may be necessary while possessing sufficient strength to withstand the pressure. With this arrangement no special accumulator is provided as the tube or rail which delivers the fuel to the engine itself furnishes the desired accumulator effect owing to its substantial volume, in conjunction with the change in volume of the fuel itself due to the high pressure of injection. The tube may be mounted so as to extend longitudinally under the fuel pressure as well as expand transversely, for which purpose a straight rail or tube may

have closed ends, the fuel being led to each injection valve through a branch pipe.

The pump may be arranged to raise the fuel pressure gradually to the high pressure required at the tube or rail, by exercising a choking action on a fuel escape during the first part of the plunger delivery stroke. The pump may be operated synchronously with the engine so that the fuel injection periods occur during the pump delivery strokes, or the pump may be partially or completely out of step with the injection periods. In the former case the tube or rail need not provide for so large a fuel charge as in the latter case.

In order that the said invention may be clearly understood and readily carried into effect, the same will now be described more fully with reference to the accompanying drawings, in which:—

Figure 1 is a front elevation and Figure 2 is a side elevation partly in section of a multi-cylinder engine provided with the improved fuel supplying means; various details shown in Figure 2 are omitted from Figure 1 for the sake of clearness.

Figure 3 is a diagrammatic front elevation of an engine showing a modified arrangement of the fuel supply.

Figure 4 is a similar diagram showing a further modification, and Figure 5 is a diagram showing the application of the invention to a single cylinder engine.

Referring first to Figures 1 and 2, A, A are the engine cylinders each provided with an injection valve B of known type, under the control of a valve operating cam C, the injection valve controlling the power of the engine by varying the period during which the liquid fuel unmixed with air is injected into the cylinder under the high pressure required. D is the fuel pump, a four plunger pump being shown in Figure 1, the fuel being introduced into the pump through the pipes d at the suction side from the chamber d' to which the supply pipe d² is connected. The pump plungers are driven from eccentrics d³ on the shaft d⁴. E is the main tube or rail extending longitudinally across the cylinders of the engine, this rail being connected to the pump by the tube F and supplying fuel to each of the injection valves B through the small bore branch pipes e for each of which is pro-

vided a cut-off cock or valve e' , a similar cock or valve e^2 being provided at the end of the tube F.

The injection valve B controls the power of the engine, since the object of the accumulation of the fuel under extremely high pressure in the rail and the connecting pipes is to maintain such pressure at the valve throughout the period of injection with as small a drop as is feasible without excessive diameter or length of tubing. The valve is operated from the cam C by a cam lever G mounted upon the adjustable eccentric fulcrum pin g on the fulcrum shaft G' and having its arm g' connected by the link g^2 to the push rod g^3 which actuates the small valve lever b of the valve B, so as to raise the latter against the pressure of its spring b' and allow of the entry of liquid fuel into the working space a of the cylinder A. Under the very high pressure of the fuel in the rail or tube system the fuel breaks into a fine spray as soon as it enters the cylinder.

The period during which the injection valve B is opened at each injection is varied in known manner by angularly adjusting the eccentric fulcrum pin g so as to bring the cam roller g^4 away from or closer to the cam C which is mounted on the cam shaft c . This is conveniently done by the hand lever H of usual type connected through the rod b to the lever j on the common control shaft J which at each cylinder carries a lever K attached to the lower end of a pair of rods L, L' connected together by a balancing lever l , the upper end of the rod L' being attached to an arm g^5 on the fulcrum shaft G'. The position of the lever H therefore determines the angular position of the fulcrum pin g .

Any individual cylinder can be cut out independently of the common control lever H by the separate operation of the lever j , which is shown of bell crank form and is not rigidly fixed to the common control shaft but can be disconnected at will and when turned into cut out position can be held by the stop j' engaging the fixed catch a' on the bracket a^2 carrying the shaft J and secured on the side of the engine.

As the pressure in the rail or tube supply system is extremely high (usually from 2000 lbs. to 6000 lbs. per square inch, but it may be considerably greater) it is desirable that the pump D should not be exposed to the shock involved in suddenly raising the pressure to this level. For the purpose of providing a relatively gradual rise during the stroke of a pump plunger the fuel is allowed to escape during the first part of the delivery stroke through a passage or channel which gives an increasing choking effect until on complete closure the full pump pressure is attained. This is effected in the pump shown by providing (see Figure 2, the pump

details being omitted in Figure 1) a suction valve M which can be held open mechanically by a rod m under the control of a small lever m' operated through the connecting rod m^2 by the lever m^3 connected to the pump plunger d^5 at the end opposite to the rod m^2 and carried on the adjustable fulcrum n provided at the end of a supporting rod n' mounted on the lever arm N connected at its outer end to the end of the pump control lever O by the adjustable connecting rod o . The lever O moves over the notched quadrant o' and is provided with a catch o^2 by which it is held in adjusted position.

The levers m' and m^3 both give large leverage so that as the plunger rod d^5 moves up for the delivery stroke it gives rise to a much smaller movement of the other end of the lever m^3 and this in its turn gives a much reduced movement to the adjustable stud m^4 on the lever m' which stud meets the rod m controlling the closing movement of the valve M. Thus as the plunger d^5 rises the stud m^4 is lowered and allows the suction valve M to close so slowly that the passage for escape of the fuel back to the suction side of the pump gives an increasing choking action before finally allowing the valve to close. The pump pressure thus gradually attains to the full pressure in the fuel supply system, whereupon fuel is delivered into the pipes leading to the cylinders and maintains the pressure of supply as the fuel is discharged through the injection valve. Owing to the capacity of the fuel supply system, including the rail E and the associated pipes, and the resilient accumulator effect there is no need for the pump delivery strokes to synchronize with the periods of injection of the various cylinders so that the pump can, if desired, be driven independently of the engine. The effective stroke of the pump is varied by altering the position of the adjustable fulcrum n by means of the control lever O, the position of the fulcrum determining the point in the pump stroke at which the suction valve M is allowed to close. Earlier closing gives a longer effective delivery stroke and later closing reduces the amount of fuel delivered.

In the pump shown (see Figure 1) the two pump casings are connected by the short branch pipes f to the main tube F through the cock or valve f' . The rail E to which the tube F leads is supported in the brackets a^3 belonging to the various cylinders and is free to expand longitudinally in the brackets, the ends of the rail having connected to them respectively a small bore tube e^3 fitted with discharge cocks e^4 and a pressure gauge tube e^5 . A tube e^6 may also be provided to connect to a rail for a second set of cylinders.

As the rail E is free to expand longitudinally under the pressure upon its ends the

resilient accumulator volume is substantially increased by the extension of the rail so that without unduly enlarging the diameter ample accommodation for the charges of fuel for the various cylinders is ensured, taking into account the compression of the fuel itself.

In the diagram, Figure 3, the arrangement is substantially similar to that already described, but the pump D is placed at one end of the engine and the tube F leads from the pump to the end of the rail E, which is placed high up so that the branch pipes e leading to the valves B are short.

In Figure 4 the pump is also at the end of the engine, but the rail E is placed low down and between the rail E and the small branch pipes e leading to the valves are large diameter tubes e' forming branching extensions of the rail and providing substantial additional accumulator volume as close as possible to the injection valves.

Figure 5 shows the application of the system to a single cylinder engine. In this case there is no longitudinal rail extending across a number of cylinders and the accumulator volume required is obtained by connecting the pump D to a large diameter fuel conducting tube or pipe E² arranged to give sufficient resilient yield to take in a charge for the single cylinder and to maintain the high pressure independently of the direct pressure due to the pump, during the opening of the injection valve.

The conditions in the tubular fuel conducting and accumulator system differ to some extent according to whether or not the fuel pump is timed in accordance with the engine stroke so that the injection of the fuel occurs during the delivery stroke of the pump. If the pump synchronizes with the firing stroke the accumulator charge necessary to maintain a high pressure at the valve may be a comparatively small fraction of a complete cylinder charge, though much greater than would be accommodated by the thick, small-bore tubes generally employed to conduct the liquid fuel to the cylinders. Where synchronization of the pump and firing strokes is arranged for the tube or rail may accommodate (within a range of pressures of say about 1500 lbs. per square inch, for example from 2500 lbs. to 4000 lbs.) only one tenth of a full cylinder charge but preferably the tube is of such volume and proportions as to allow of the resilient accumulation under such range of pressures of a substantially larger fuel volume, say, a quarter, a third, a half or more of a full single cylinder charge. The pump is not usually adapted to deliver exactly in synchronism with the injection period, since the fuel charge has to be injected into the cylinder during a very short period of opening of the valve and unless there is a sub-

stantial accumulator effect provided for it is difficult to maintain the required high pressure of injection during the rapid discharge. The tube or rail must, therefore, for the purposes of this invention, compensate for any differences between the fuel discharge through the injection valve and the rate of delivery from the pump, so as to prevent the pressure at the injection valve falling below a high level.

Where the pump is driven (as would commonly be the case in a multi-cylinder engine) without synchronizing with the firing strokes, or synchronizing only at intervals, the tube or rail must accommodate a much larger volume of fuel within the range of allowable pressures, preferably about a full cylinder charge or more at a pressure range of about 1500 lbs.

The following is an example of an engine embodying this invention. A six cylinder engine having a full cylinder charge of about 0.8 cubic inch of fuel employed a pump driven at about 4.135 strokes per revolution of the engine shaft, the pump delivering into a tube or rail system having a capacity of 256 cubic inches at a maximum pressure of about 4000 lbs. per square inch. The capacity of the tubular fuel conducting system (256 cubic inches) is many times that which has been employed merely to lead the fuel from the pump to the cylinders and in the engine referred to the rise and fall of pressure due to the admission and withdrawal of the charge of about 0.8 cubic inch is in the neighbourhood of 1000 lbs. per square inch.

The supply of a full charge of fuel to a cylinder when the pump delivery stroke is entirely out of phase with the firing stroke is therefore ensured and ample margin is provided for any probable irregularities in the action of the pump or of an injection valve.

The above engine is one in which the pump is out of synchronism with the engine, but even in engines with approximately synchronous pump delivery and firing strokes it is desirable to employ a large tube volume, in case of partial or complete failure of a pump stroke due to leakage of a gland, dirt under the valve or accidental admission of air or other cause; or to irregularities of action at the injection valves. Such large accumulator volume as is given above is however not essential, although perhaps desirable, where the pump operates synchronously with the engine.

What I claim and desire to secure by Letters Patent of the United States is:—

1. In a multicylinder internal combustion engine, a plurality of cylinders, an injection valve for liquid fuel unmixed with air at each cylinder, mechanism for opening said valves in the required order and for regulated periods, a fuel supply conduit for a plurality

- of cylinders leading to each of said injection valves, a liquid fuel pump connected to the said common fuel supply conduit, said fuel supply conduit having relatively thin walls 5 and relatively large cross-sectional area for a substantial portion of its length to give sufficient elasticity to distort under the pressure of the fuel in the supply conduit to increase the capacity of the fuel supply conduit, whereby upon the opening of one of said injection valves the fuel supply conduit contracts sufficiently to inject a charge of fuel into one of the said cylinders without the use of any special accumulators in the 10 fuel supply system to obtain the proper injection of a charge of fuel into one of the said cylinders.
2. In a multicylinder internal combustion engine, a plurality of cylinders, an injection valve for liquid fuel unmixed with air at each cylinder, mechanism for opening said valves in the required order and for regulated periods, a fuel supply conduit for a plurality of cylinders leading to each injection valve, a liquid fuel pump connected to said fuel supply conduit, means for actuating said pump to pump fuel intermittently into said conduit out of synchronism with the opening of the injection valves, said conduit having relatively thin walls and relatively large cross-sectional area for a substantial portion of its length to give sufficient elasticity to distort under the pressure of the fuel in said conduit when said injection valves are closed to increase the capacity of the fuel supply conduit and to contract upon the opening of one of said injection valves to inject a charge of fuel into one of said cylinders without the use of any special accumulators in the fuel supply system to obtain the proper injection of a charge of fuel into one of the said cylinders.
3. In a multicylinder internal combustion engine, a plurality of cylinders, an injection valve for liquid fuel unmixed with air at each cylinder, mechanism for opening said valves in the required order and for regulated periods, a fuel supply conduit for a plurality of cylinders leading to each injection valve, a liquid fuel pump connected to the said fuel supply conduit, means for actuating said pump to pump fuel intermittently into the fuel supply conduit out of synchronism with the opening of the injection valves, said pump having a fuel discharge passage and means for slowly closing said discharge passage during the first part of the delivery stroke of said pump to exercise an increasing choking action on the fuel and raise the pump pressure gradually to the limit required to inject the fuel into the cylinders at the proper pressure, said fuel supply conduit having relatively thin walls and relatively large cross-sectional area for a substantial portion of its length 65 to give sufficient elasticity to distort under the pressure of the fuel within it to increase its capacity when the injection valves are closed and upon the opening of one of said injection valves to contract and inject a 70 charge of fuel into one of said cylinders without the use of any special accumulators in the fuel supply system to obtain the proper injection of a charge of fuel into one of the said cylinders. 75
4. In a multicylinder internal combustion engine, a plurality of cylinders, an injection valve for liquid fuel unmixed with air, mechanism for opening said valves in the required order and for regulated periods, a fuel supply tube common to all the cylinders, connections from said tube to each injection valve, and a liquid fuel pump connected to said common fuel supply tube, said tube having relatively thin walls and relatively 80 large cross-sectional area for a substantial portion of its length to give sufficient elasticity to distort under the pressure of the fuel in the tube and to contract when one of the said injection valves is opened to 85 inject a charge of fuel into one of the cylinders without the use of any special accumulators in the fuel supply system to obtain the proper injection of a charge of fuel into one of the said cylinders. 90
5. In a multicylinder internal combustion engine, a plurality of cylinders, an injection valve for liquid fuel unmixed with air at each cylinder, mechanism for opening said valves in the required order and for regulated periods, a fuel conducting tube common to a plurality of cylinders, supporting means for said tube permitting free expansion and contraction of said tube longitudinally and transversely, connections from 100 said tube to each injection valve, a liquid fuel pump connected to said fuel conducting tube, said fuel conducting tube having relatively thin walls and relatively large cross-sectional area for a substantial portion of 105 its length to give sufficient elasticity to distort under the pressure of the fuel within the same to increase the fuel carrying capacity of said tube and upon the opening of one of said injection valves to contract 110 and inject a charge of fuel into one of said cylinders without the use of any special accumulators in the fuel supply system to obtain the proper injection of a charge of fuel into one of the said cylinders. 115

JAMES McKECHNIE.
